UNITED STATES PATENT OFFICE.

HUGO GROSSENBACH, OF BROOKLYN, AND WILHELM PANHORST, OF NEW YORK, N. Y.

CARRIER OR RACER FOR BRAIDING-MACHINES.

SPECIFICATION forming part of Letters Patent No. 445,815, dated January 27, 1891.

Application filed April 29, 1890. Serial No. 349,912. (No model.)

To all whom it may concern:

Be it known that we, HUGO GROSSENBACH and WILHELM PANHORST, the former of Brooklyn, Kings county, in the State of New 5 York, and the latter of New York city, in the same State, have invented a certain new and useful Improvement in Carriers or Racers for Braiding-Machines, of which the following is a specification.

10 The object of our invention is to reduce and render uniform the tension of the yarn as it is taken off the bobbin to be conducted into the braid. The resistance offered to the unwinding of the yarn from that point which is 15 opposite the guide-eye is the minimum, while when the yarn is drawn through the eye from other parts of the spool the resistance will be greater, this increase being largely due to the friction of the strand in unwinding against 20 the body of the yarn upon the spool. The inequality in the resistance is less as the distance of the guide-eye from the point of unwinding is increased. We have devised simple means which tend to equalize the resistance, increasing 25 it when the yarn is drawn from the point of the spool nearest the guide-eye and tending to decrease it when it is drawn from more distant points. We attain both these ends by means of a straight smooth round bar or 30 wire parallel to the guide-bar, but considerably to one side thereof and out of contact with the spool. The yarn is deflected to pass this bar in being led from the spool to the usual eye in the guide. At the point of the 35 spool opposite the eye the yarn runs horizontally over the deflector-bar, while as it unwinds from more distant points it assumes an oblique position; but the angle of obliquity is less than heretofore by reason of the increased 40 length of the traverse of the yarn in passing from the spool. The reduction in the angle makes the pull of the yarn more direct to induce the proper delivering motion of the spool.

45 Our invention may be used with all the ordinary provisions for stop-motions and the like.

The accompanying drawings form a part of this specification and represent what we consider the best means of carrying out the in-

vention. Figure 1 is a side elevation. Fig. 2 is a horizontal section on the line *x* *x* in Fig. 1.

Similar letters of reference indicate corresponding parts in both the figures where they appear.

We have represented the invention as applied to a carrier having an ordinary form of stop-motion, with a hollow spindle and a weight inside in addition to the ordinary weight running on the guide, and will describe it as thus used; but it will be understood that these points may be varied.

A is the body of the carrier, *A'* the spindle, and *A²* the collar on which the spool rests.

A³ is the guide, having an ordinary smooth eye *a*, through which the yarn is conducted.

B is a spool, and *C* the yarn delivered therefrom through the eye.

On the collar *A²* is a sufficiently stout horizontal arm *A⁴*, reaching out beyond the flange of the spool. On this arm we rigidly mount a straight rod of iron or steel *A⁵*, extending upward to a sufficient distance to serve as a deflector for the yarn in being delivered from all parts of the longest spools. The yarn *C* is led from the spool to this rod, and, performing about a quarter-circuit around this latter, extends thence to the eye, after passing which it may be caused to operate the stop-motions, and is led away to be wrought into the braid in any ordinary or suitable manner.

The exigencies of the work require that the carrier shall possess but moderate lateral dimensions. The guide *A³* stands, necessarily, almost in contact with the rims of the spool. Whether the spool is full or empty, the yarn has but a little distance to traverse on leaving its coil on the spool and passing out through the eye. Our deflector *A⁵* compels the yarn to traverse farther than usual. It increases the available space between the surface of the yarn on the spool and the eye. By so doing it reduces the angle at which the yarn leaves its place on the spool. The increase in the directness of the pull of the yarn on the rotation of the spool in the extreme portions results in reducing the tension when the yarn is being taken from those parts of the spool. When the yarn is being taken

from the coils at that portion of the spool level with the eye, our invention increases the resistance. This increase is due to the fact that the yarn, instead of being pulled directly 5 from the periphery of the spool into the eye, and thus inducing at the eye only the tension which is required to pull the spool around, is by our invention required to turn about a right angle in passing partially around the 10 deflector A⁵. The considerable friction induced by this traverse of the yarn partially around the deflector makes a corresponding increased tension on the yarn under this condition. The eye a may come opposite the 15 mid-height of the spool or it may, as usual, be considerably higher. Our deflector will serve with a wide range of lengths of spool and with the eye placed considerably lower or even higher than shown. The rod A⁵ is of 20 a length sufficient for the longest spool. To adapt the machine for a longer or shorter spool, the pinching-screw a² is slackened and the collar A² is raised or lowered.

We deem it important that the rod A⁵ be 25 carried by the collar A² instead of by the guide-arm, and that it be arranged between the guide-eye a and the guiding-eye b, as shown, out of diametric line with the guide-

eye a and the center of the spool, as seen in Fig. 2, so that the yarn is taken from the 30 spool parallel with the said guide a and then turned at right angles thereto over the rod A⁵, as seen best in Fig. 2, so as to increase the friction and consequently the tension on the yarn. Where the deflector-rod is carried 35 by the guide-arm, it is difficult to arrange it in the position deemed most desirable to obtain the desired results.

We claim as our invention—

A carrier for braiding-machines, having a 40 spool-supporting spindle, a standard provided with a yarn-guiding eye, and with a deflector-rod A⁵ placed parallel with the spindle and carried by the collar on which the spool rests independent of the guide, substantially as 45 shown and described.

In testimony whereof we have hereunto set our hands, at the city of New York, this 25th day of April, 1890, in the presence of two subscribing witnesses.

HUGO GROSSENBACH.
WILHELM PANHORST.
